Primary Examiner — Catherine Tuttle

CLAIM

The ornamental design for a ball, as shown described.

DESCRIPTION

FIG. 1 is an isometric view of the ball showing my new design;
FIG. 2 is a front elevation view thereof;

FIG. 3 is a right side elevation view thereof;

FIG. 4 is a rear elevation view thereof;

FIG. 5 is a top plan view thereof; and,

FIG. 6 is a bottom plan view thereof.

The left side elevation view is a mirror image of the right side.
